US00D664106S

(12) **United States Design Patent**
Kobayakawa et al.

(10) **Patent No.:** US D664,106 S
(45) **Date of Patent:** ** Jul. 24, 2012

(54) **LIGHT EMITTING DIODE MODULE**

(75) Inventors: **Masahiko Kobayakawa**, Kyoto (JP);
Takashi Moriguchi, Kyoto (JP)

(73) Assignee: **Rohm Co., Ltd.**, Kyoto (JP)

(**) Term: **14 Years**

(21) Appl. No.: **29/399,073**

(22) Filed: **Aug. 9, 2011**

(30) **Foreign Application Priority Data**

Feb. 10, 2011 (JP) 2011-002825

(51) **LOC (9) Cl.** 13-03

(52) **U.S. Cl.** D13/180

(58) **Field of Classification Search** D13/180;
D26/1, 2; 257/79, 80, 81, 88, 89, 95, 98,
257/99, 100, E33.058; 313/483, 498, 500;
362/555, 800

See application file for complete search history.

(57) **CLAIM**

We claim the ornamental design for a light emitting diode module, as shown.

DESCRIPTION

FIG. 1 is a perspective view of a light emitting diode module according to our new design;

FIG. 2 is a front view of the same module;

FIG. 3 is a rear view of the same module;

FIG. 4 is a top plan view of the same module;

FIG. 5 is a bottom view of the same module;

FIG. 6 is a right side view of the same module; and,

FIG. 7 is a left side view of the same module.
